BASKETBALL BACKSTOP

Michael Hornung and Victor W. Claussen, Spearville,
Kans., assignors to EZ Fold, Inc., Spearville, Kans.

Application April 13, 1955, Serial No. 35,492

Term of patent 14 years

(Cl. D34—5)

FIG. 2

FIG. 1

FIG. 3

FIG. 4

Fig. 1 is a front elevation of a basketball backstop showing our new design;

Fig. 2 is a side elevation of same;

Fig. 3 is a rear elevation of same; and

Fig. 4 is a bottom view of same.

The dominant features of our new design are shown in solid lines in the drawing. The broken line showing of an I beam support is for illustrative purposes only.

We claim:

The ornamental design for a basketball backstop, substantially as shown and described.
